Assistant Examiner—A. O. Davis

[57] **CLAIM**

The ornamental design for a post-operative knee rehabilitative dynamometer, as shown.

DESCRIPTION

FIG. 1 is a front elevational view of the post-operative knee rehabilitative dynamometer showing my new design;

FIG. 2 is a rear plan view of the post-operative knee rehabilitative dynamometer with hose and gauge removed;

FIG. 3 is a right side plan view of the post-operative knee rehabilitative dynamometer with the hose and gauge removed;

FIG. 4 is a bottom plan view of the post-operative knee rehabilitative dynamometer with the hose and gauge removed; and,

FIG. 5 is a left side plan view of the post-operative knee rehabilitative dynamometer with the hose and gauge removed.
